BURNER HEAD AND MOUNTING

Joseph T. Voorheis, Oakland, Calif.

Application August 19, 1941, Serial No. 407,447

5 Claims. (Cl. 158—73)

This invention relates to a burner head and mounting, and especially to improvements in the construction and assembly of the burner head and mounting disclosed in my former Patent No. 1,533,482, entitled "Burner head and mounting," issued April 14, 1925.

In the operation of oil burners of the type here shown, whether it be in a factory, boiler plant, or on board ship, or otherwise, it sometimes happens that carbon forms in the burner tip or atomizing nozzle, due to the radiant heat of the furnace to which it is exposed. This usually happens during a momentary shut-down of the burner, and causes partial or complete stoppage of oil flow when the oil is again turned on. On board ship, when maneuvering or making a landing, or when a full head of steam is required for operating, it is obviously necessary quickly to replace the clogged burner with a clean one, as the steam pressure may otherwise drop too low, or the furnace may cool down to such an extent as to cause flarebacks or other disastrous results.

The object of the present invention is generally to improve and simplify the construction and operation of burner heads and mountings of the character described; to provide a burner head and mounting which permit a change of burners in a minimum of time; to provide a socket and head fitting for the burner head, whereby the connection between the burner head and the oil supply line can be made rapidly; to provide means on the mounting for aligning the socket and head fitting when making the oil line connection; and further, to provide separable socket and head fittings, which may be removed and replaced in the burner head and mounting when wear or damage to said fittings takes place.

The improved burner head and mounting is shown by way of illustration in the accompanying drawings, in which

Fig. 1 is a side elevation of the burner head and mounting partially in section;

Fig. 2 is a front view thereof; and

Fig. 3 is a section similar to Fig. 1 showing a modified structure.

Referring to the drawings in detail, and particularly to Fig. 1, A indicates in general a mounting plate which may be suitably secured or supported in front of a furnace, not here shown, and removably secured on said mounting plate is a burner head, generally indicated at B, which carries a burner tube 2 and a nozzle not shown.

The mounting plate is elongated and vertically disposed. At the upper end thereof is formed a hollow boss 4 which supports and secures a combination guide and shielding tube 5, through which the burner tube and nozzle not shown extend. In the outer end of the boss is formed an annular shoulder 6, and on the face thereof is formed a seat 7, the function of which will hereinafter be described. Extending outwardly from the mounting plate A and at right angles thereto are a pair of arms 8—8, which are connected at their outer ends, as shown at 9. These arms and their connection form a yoke which supports a clamping screw 10, whereby the burner head is secured in position when in operation. Formed at the lower end of the mounting plate A and in central alignment between the arms of the yoke and the clamping screw 10 is an opening 11 in which is secured, by means of 10 a nut 12, a seat fitting 14. One end of this fitting is threaded to permit it to be connected with a pipe line which in turn is connected with a suitable source of oil supply under pressure. The opposite end of the fitting has a spherical 15 seat 15 formed thereon, which is adapted to receive a cooperating fitting 16 carried by the burner head. The burner head has an inlet end 17 and a discharge end 19, these ends being connected by an arcuate arm 20 in which is formed 20 a passage 21 to convey oil from the inlet to the discharge. The inlet end 17 has a threaded 25 opening formed therein to receive the fitting 16, the outer end of said fitting being spherical to engage the socket seat 15 of the fitting 14. 30 The discharge end 19 of the burner head has an interior chamber 22 formed therein and at one end an annular shoulder 23 to receive and support a strainer tube 24. The opposite end of the discharge member 19 is threaded to receive a closing plug 25, and this is provided with an annular recess 26 to receive and clamp the strainer tube when in position, a suitable handle 27 being formed on the closing plug to permit the burner head to be manipulated readily. Also 35 formed on the discharge end of the burner head is an annular seat 7a which cooperates with the seat 7 of the boss 4. These two seats substantially engage when the burner head is clamped into position, as do the seats formed on the fittings 15 and 16. On the lower side of the discharge end of the burner head is formed a lug 28, and in the lower part of the boss there is a recess 29. The lug 28 enters this recess when the burner head is placed in position, and it 40 secures the burner head against rotation and at 45 50

the same time insures positive alignment between the inlet fittings 15 and 16.

In actual operation, oil will enter through the feed pipe 30 and the flow may be controlled by a valve 31 in the usual manner. The oil passes through the fittings 15 and 16, then through the hollow passage formed in the arcuate arm 20, then through the strainer tube 22 and into the burner tube 2, which in turn feeds an atomizing nozzle.

The steam requirements of a boiler vary with the load, and at certain times it may be necessary to momentarily shut off the oil supply, or, in other words, to cut off the burner. If the shut-down is merely momentary, the burner need not be removed, but if the shut-down lasts for several minutes, the burner should be removed, as the radiant heat of the furnace will heat the atomizing nozzle to such an extent that the oil will tend to carbonize and clog the passages thereof. If this happens, it is essential that the burner be removed and that it quickly be replaced with a new clean burner, as a full head of steam must be maintained, particularly on board ship, for instance, when maneuvering to make a landing, or the like.

In the present instance, if an atomizing nozzle should clog, it would be necessary only for the operator to close the valve 31 and to slacken up on the clamping screw 10. The moment he does so, the burner head becomes free and may be grasped by the handle 27 and rotated in a clockwise direction, causing the arcuate arm 20 of the burner head to swing the inlet end 17 and the fitting 16 thereof outwardly from between the arms of the yoke. When this has been done, the burner is pulled out of the guide and shielding tube 5 and a new burner may be inserted. When this has been inserted, the arcuate arm 20 is swung downwardly until its lower end enters between the arms of the yoke. The burner head is then shoved inwardly to engage the seat members 7 and 7a, and to cause the lug 28 to enter the recess 29. At this point the fittings 15 and 16 are aligned and the operation is completed by merely tightening the clamping screw 10.

In removing and inserting the burner head, and after removal, when the burner head is lying on a bench, there is a possibility that the seat at the outer end of the fitting 16 may be damaged. If this happens, the fitting 16 may be unscrewed and a new one inserted, and the same is true of the fitting 14. It is for this reason that they are removable and renewable. The seats between the fittings 15 and 16 are preferably spherical, and the center of the sphere should be approximately midway between the seating surfaces of said fitting and the point where the clamping screw engages. That point is formed by a slightly raised boss 7a which is also machined to the same spherical surface, and so is the end of the clamping screw 10. By so doing all surfaces are more readily aligned and seated.

The entire structure is exceedingly simple in construction; machine work, and cost of manufacture are reduced to a minimum; and above all, quick insertion and removal of the burner and burner head is permitted.

In Fig. 3 a modified form of burner head is shown which is particularly designed for use in conjunction with the type of atomizing nozzle shown in my co-pending application entitled, "Methods and means of atomizing liquids," filed December 9, 1940, Serial No. 369,224. In the nozzle structure there disclosed, a return pipe for

excess oil is provided; hence, the burner head shown in Fig. 3 is provided with two passages such as indicated at 33 and 34. The passage 33 serves as the supply or inlet just as the structure shown in Fig. 1 and discharges into pipe 2a which delivers it to the nozzle. The return oil flows through a pipe 2b and this connects with the passage 34. Seat fittings are provided at the lower end of both passages and are held in engagement with cooperating fittings by a clamping screw 10a, the only difference being that an outlet block 35 is provided which is connected to a return pipe 36. The block is slidably mounted on a pair of rods 37 and it is positively moved when the clamping screw 10a is actuated due to the connection shown at 38. Thus the lower end of the burner head is released from between the fittings when the clamping screw is released as the fittings are actually separated, and is conversely secured when the clamping screw is tightened as the fittings are then brought together.

While the burner head shown in Fig. 3 is particularly designed for a return flow of oil, it may obviously be used in connection with atomizing nozzles employing steam or compressed air as one of the passages in the burner head can supply oil, and the other steam or air as the case may be, and while these and other features of my invention have been more or less specifically described and illustrated, I nevertheless wish it understood that changes may be resorted to within the scope of the appended claims, and that the materials and finish of the various parts employed may be varied according to what the experience of the manufacturer and varying conditions of use may demand.

Having thus described my invention, what I claim and desire to secure by Letters Patent is—

1. In a device of the character described, a burner head having an inlet end and a discharge end, an arcuate arm connecting said ends and having a passage formed therein to convey oil from the inlet end to the discharge end, a mounting to receive and support the burner head, said mounting comprising an elongated plate having an upper and a lower opening formed therein, a yoke having a pair of spaced arms secured to the plate and extending outwardly from the plate, said yoke aligning with the lower opening in the plate, a burner tube secured to the discharge end of the burner head and adapted to extend through the upper opening in the plate and to form a swivel-like support for the burner head to permit the inlet end to be swung inwardly between the arms of the yoke to align with the lower opening, a seat fitting connected with a source of oil under pressure secured in the lower opening, and a clamping screw carried by the yoke engageable with the burner head to secure the inlet end thereof in seated engagement with the seat fitting when oil is to be conveyed to the burner pipe.

2. In a device of the character described, a burner head having an inlet end and a discharge end, an arcuate arm connecting said ends and having a passage formed therein to convey oil from the inlet end to the discharge end, a mounting to receive and support the burner head, said mounting comprising an elongated plate having an upper and a lower opening formed therein, a yoke having a pair of spaced arms secured to the plate and extending outwardly from the plate, said yoke aligning with the lower opening in the plate, a burner tube secured to the discharge end of the burner head and adapted to extend through

the upper opening in the plate and to form a swivel-like support for the burner head to permit the inlet end to be swung inwardly between the arms of the yoke to align with the lower opening, a seat fitting connected with a source of oil under pressure secured in the lower opening, a clamping screw carried by the yoke engageable with the burner head to secure the inlet end thereof in seated engagement with the seat fitting when oil is to be conveyed to the burner pipe, and means cooperating with the discharge end of the burner head for aligning the inlet end of the burner head with the seat fitting when swung inwardly between the arms of the yoke.

3. In a device of the character described, a burner head having an inlet end and a discharge end, an arcuate arm connecting said ends and having a passage formed therein to convey oil from the inlet end to the discharge end, a mounting to receive and support the burner head, said mounting comprising an elongated plate having an upper and a lower opening formed therein, a yoke having a pair of spaced arms secured to the plate and extending outwardly from the plate, said yoke aligning with the lower opening in the plate, a burner tube secured to the discharge end of the burner head and adapted to extend through the upper opening in the plate and to form a swivel-like support for the burner head to permit the inlet end to be swung inwardly between the arms of the yoke to align with the lower opening, a seat fitting connected with a source of oil under pressure secured in the lower opening, a clamping screw carried by the yoke engageable with the burner head to secure the inlet end thereof in seated engagement with the seat fitting when oil is to be conveyed to the burner pipe, a lug on the discharge end of the burner head, and a seat formed in the plate adjacent the upper opening formed

therein to receive said lug, said lug and seat assuring alignment of the inlet end of the burner head and the seat fitting.

4. In a device of the character described, a 5 mounting plate, a burner head adapted to be supported thereby, said head having two ends with one opening formed in one end and two openings in the opposite end which face in opposite directions, said head also having a pair of 10 passages formed therein connecting the openings in the opposite ends in a manner to form two separated flow passages, a fixed seat fitting and a slidable seat fitting carried by the mounting plate between which the end of the burner 15 head having the opposed openings formed therein is adapted to be introduced, and means engageable with the slidable seat fitting to clamp the burner head between the fixed and the slid- 20 able fittings so that fluid under pressure may be introduced through the fittings into the flow passages of the burner head.

5. In a device of the character described, a mounting plate, a burner head adapted to be supported thereby, said burner head having an 25 inlet and an outlet at each end, and separated 30 passages connecting said inlets and outlets, a pair of pipes one extending through the other, connected with the inlet and outlet at one end of the burner head, said inlet and outlet at the opposite end of the burner head facing in opposite directions, a pair of seat fittings carried by the mounting plate, and engageable with the opposed inlet and outlet, one of said fittings being slidably mounted to permit separation of the 35 fittings when introducing the burner head, clamping means engageable with the slidable fitting to clamp the burner head between the fittings and a pipe connected with each fitting.
